UNITED STATES PATENT OFFICE.

FERDINAND THIELKE, OF BROOKLYN, NEW YORK.

DESIGN FOR A HANDLE FOR BUTTON-HOOKS.

SPECIFICATION forming part of Design No. 28,391, dated March 22, 1898.

Application filed December 29, 1897. Serial No. 664,478. Term of patent 3½ years.

To all whom it may concern:

Be it known that I, FERDINAND THIELKE, a citizen of the United States, residing at Brooklyn, in the county of Kings and State of New York, have invented and produced a new and original Design for Handles for Button-Hooks and Like Articles, of which the following is a specification, reference being had to the accompanying drawing, which shows a side view of my newly-designed handle applied to a button-hook.

The leading feature of my design consists of the outline as shown, consisting of compound curves, and having raised border-lines running parallel with the outer edge, the outer end of the handle terminating in a fleur-de-lis, the handle being further ornamented with several fleurs-de-lis separating plain shields.

A represents the handle, having the contour or outline as shown and provided with raised lines B, running parallel with the outer edge.

C represents a fleur-de-lis, in which the outer end of the handle terminates.

D E represent fleurs-de-lis separating the plain portions F G H.

What I claim is—

A design for a handle for button-hooks, and similar articles, substantially as herein shown and described.

FERDINAND THIELKE.
